UNITED STATES PATENT OFFICE.

LOUIS H. THULLEN, OF EDGEWOOD PARK, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING SYSTEM.

No. 839,525.

Specification of Letters Patent.

Patented Dec. 25, 1906.

Application filed January 4, 1904. Serial No. 187,651.

To all whom it may concern:

Be it known that I, LOUIS H. THULLEN, a citizen of the United States, residing at Edgewood Park, in the county of Allegheny and State of Pennsylvania, have invented certain new and useful Improvements in Railway Signaling Systems, of which the following is a specification.

My invention relates to systems of signaling by alternating currents on electric railways. In applying such a signaling system to electric railways one of the rails is made electrically continuous—that is, without portions thereof being insulated from each other. The other rails are divided into sections corresponding to what are known as "block-sections," the adjacent ends of the rails of each section being insulated from each other.

By the present invention I employ both the continuous and the sectional rail as a return-path for the car-propulsion current.

Referring to the drawings, Figures 1 to 6 are diagrammatic views, each showing a different form which my invention may assume.

Referring now to Fig. 1, A designates a direct-current generator furnishing current for the car-motor traveling along the railway. One terminal of the generator A is connected to the trolley-wire or third rail B and the other terminal to the track-rails, which form the return-path for the propulsion-current. The track, which comprises a continuous rail M and a rail N, is divided into block-sections F F' F'', &c., by providing insulation H at points in the rail N to form insulated sections. n n' n'', &c., designate the insulated sections of the rail N. Each block-section corresponds to the length of the sections into which the rail N is divided by the insulations. At the entrance end of block-sections a railway signal C is provided, which signals govern the passage of trains into the block-sections. At D, I represent graphically a car bridging the rails M and N and provided with a trolley-pole or electric connector d, which contacts with the trolley-wire B. E designates transformers having their primaries shown connected in series with an alternating-current generator L or other source of alternating-current supply and their secondaries e (except those at the ends of the tracks) bridging the insulations H—that is, the secondaries have one ter-

55 minal connected to one end of a rail-section and the other terminal to the adjacent end of the adjacent rail-section. The secondary windings are composed of a few turns of copper bars and are of low ohmic resistance, approximately equal to the resistance of the rails, and furnish a path of low ohmic resistance for the car-propulsion current from one rail-section to another. At each end of each block-section I preferably place an inductive cross-bond G, which connects the ends of the rail-sections to the continuous rail. Each cross-bond comprises a coil g and furnishes a path of low resistance to neutralize the difference of potential in power-current between the track-rails caused by any difference in resistance that may exist in the track-rails. These inductive bonds also furnish paths for the alternating current generated by the transformers E E', &c.—that is, the bonds G at the adjacent ends of the block-sections F and F' furnish a path for the alternating current sent from the correspondingly-located transformer E'—and the bonds G at the adjacent ends of the block-sections F' and F'' furnish paths for the alternating current from the correspondingly-located transformer E'', and so on with the other coils in the cross-bondings. In other words, each transformer E supplies alternating current to the ends of the block-sections adjacent which they are located. 85 Relays K, responsive to the alternating signaling-current, are connected in multiple to the rails M and the sections of rail N. A relay is connected at each end of the section F' and a relay at each end of the section F'', and a relay K is connected at each end of the section F''. These relays may be of any of the well-known types which respond to alternating current and are used in signaling systems of this type.

95 Where there is but one relay to a block the switch-arm k closes or connects the contacts o of the local circuit which controls the railway-signal for that block. The railway-signals may be of any type, but preferably of the semaphore type. When the local circuit of a railway-signal is closed, the semaphore thereof is held in its clear or safety position, and when said circuit is open it is moved to its danger position. When a train is on a block, its wheels and axles shunt or short cir-

cuit the relay or relays for that block, thereby causing the relay arm or arms k to move from the contacts o , whereupon the railway-signal displays a danger indication.

5 Where there are two or more relays to a block, the contacts o at each relay are all in series, and consequently when one set of the contacts o is opened the circuit which controls the railway-signal for that block is 10 opened.

The object of connecting a relay to both ends of a block-section is to have the currents which control the railway-signals go through both relays, so that if a train should 15 shunt the relays by being in the block to which the said relays are connected the signals will operate. If there should be a break in either rail between the two transformers at opposite ends of a block-section and a 20 train should enter this block-section it would shunt one of the relays, but not the other; but as each relay controls the signal the latter would operate. Any number of relays could be placed between the two end relays of a 25 block-section. Also, if desired, a relay could be connected as the relay for block-section F^3 is shown connected. This relay which is at one end of the block-section F^3 is shown connected by wires to the other end of said section, so that a train shunting the terminal of 30 these wires where they are connected to the track will shunt the relay, even if one of the rails be broken between the points to which the two sets of connections of the relays are 35 made. Other branch wires may similarly connect the relay to other selected points in the block-section, if desired, as shown in Fig. 3, in order to provide more points at which the relays may be shunted in case of breaks 40 in the rails or of defective bonding or other break in the rail-circuits. I do not specifically claim this arrangement in this application, but do claim a relay that is operated by current from a plurality of points in the 45 track-circuit.

I have placed the primaries of the transformers E , &c., in series with the generator L , so that a train entering a block-section and short-circuiting the secondaries will not 50 injure the transformers by an excessive flow of current in the primaries and secondaries thereof. The primaries may be connected in parallel, however, as shown in Fig. 2, or in Fig. 4, where impedance-coils Z are inserted 55 in the primaries to limit the flow of current when the secondaries are short-circuited by trains.

Referring to Fig. 2, the reference-letters are the same as on Fig. 1 where the parts 60 are the same. Each of the transformers E has its primary coil connected in multiple with the alternating-current generator L and its secondary coil in parallel with the continuous rail M and one of the rail-sections. 65 I provide transformers X , whose primary

coils each have one of their terminals connected to the end of one rail-section and the other terminal connected to the end of the adjacent rail-section, except that the terminal 70 transformers, as the left-hand one, has its terminals bridged across the rails M and N . The windings of the primary coils of these transformers being composed of a few turns of heavy copper bar or cable afford low-resistance paths for the direct-current propulsion-current from the direct generator A , approximately equal to or less than the resistance of the rails. The secondaries Y of the 75 transformers X are connected together in pairs, the members of each pair being in series. The 80 terminals of the pairs are connected to the trolley-wire B or any source of direct-current supply to the transformers at the points R and R' , which are at some distance from each other, so that there will be a difference of 85 direct-current potential at the said points R and R' , due to the resistance of the trolley-wire B . This difference of potential will be in proportion to the current traversing the wire B and will also bear a definite ratio to 90 the direct current in the rail return. The secondaries of the transformers X are so connected that normally they will be traversed by little, if any, alternating current—that is, the secondaries will be connected together 95 through the medium of the wire B , so that the alternating current generated in the secondary of one transformer will oppose the alternating current generated in the secondary of the other transformer. The inductive 100 resistances V , placed between the points R and R' and one of the transformers X , prevent an excessive flow of alternating current through the secondaries when the primary of one transformer X of a pair whose secondaries are 105 in series is short-circuited. I have shown the secondaries connected in pairs; but it is clear that three or more could be connected together in series between selected points R and R' . The object of connecting the secondaries Y to the trolley-wire, feeder, or 110 third rail B , as described, is to neutralize the magnetism of the core caused by the direct current which passes from the rail N through the primaries. The difference of direct-current potential at the connecting-points R and R' is in proportion to the current traversing the rails and the primaries of the transformers. The number of turns in the secondaries 115 and the direction of the direct current in them are so connected and proportioned as to 120 approximately eliminate the magnetism of the core due to the direct current in the primaries. As the transformers X are between the ends of the sections of the rail N , the counter electro-motive force set up in the transformer will 125 keep any large amount of alternating current from passing on the rail N from one block-section to another. Hence, for example, an alternating current set up by the transformer 130

E in the rails of the block-section F' will control the relay K of that block-section and cannot have any effect on the relays of the other block-sections. The less the alternating current flowing in the secondary of any transformer and the less the core thereof is magnetized by the direct current the less will be the flow of alternating current from one section to another. The cross-bondings G are shown at the ends of some of the block-sections; but they may be used or not, as the case demands, their purpose being the same as in Fig. 1. The relays K are connected the same as in Fig. 1, two relays being used for block F' and one each for blocks F² and F³; but any number of relays to a block may be used. The transformers E are shown connected one at one end of each block and furnishing alternating current for that block. A resistance P, either inductive or non-inductive, is connected in series with the secondary of each transformer, if the transformers are connected in multiple, as shown, in order to limit the flow of alternating current through the secondary when it is short-circuited by the trains. If the transformers be connected in series, as in Fig. 1, these resistances will not be needed, as explained under the description of said figure. I do not limit myself to the inserting of resistance between the secondary and the track, as it is well known that a transformer can be used with a large leakage factor, the secondary of which can be short-circuited without abnormal flow of current in the primary.

Referring now to Fig. 3, the transformers E have, as in Fig. 1, their secondaries e connected between the ends of the insulated rail-sections and their primaries e' connected in series with the source L of alternating current. The secondary coils being composed of heavy copper bar or cable have but few turns and afford paths of low resistance for the return-current to the generator A, and besides supply current to the block-sections. The primaries e' could be connected in multiple, as in Fig. 2 or Fig. 4, by inserting the resistance P or Z to limit the flow of alternating current when trains short-circuit the secondaries e. The transformers E are provided with additional coils e², connected in series with the direct-current generator U, whose field-winding u is connected to the rails M and N, and therefore traversed by the direct current, which traverses the secondaries e from the generator A. Therefore the current generated by the dynamo U and traversing the coils e² is in a definite proportion to the current in the field-winding u of the dynamo U and in the rail-sections bridged by the coils. The windings of the coils e² are such that the current generated in one will oppose the current generated in the one next to it. The turns of the coils and the direction of direct current in the windings e² of the

transformers E are such as to approximately neutralize the magnetism of the core caused by the direct current traversing the windings e. The cross-bondings G are used as in Fig. 1, and the block-section F' is shown with one relay and the section F² with two relays, connected as in Fig. 1, except that the single relay of the section F' has connection with the rails at three points instead of at two points, as shown for the block-section F³ of Fig. 1. The number of connections will be sufficient for the conditions of each particular block, the plural connection being provided, as before explained, to cause the signals C of a block to be actuated if a break or its equivalent should occur in a rail between the train and the relay of the block on which the train is running.

Referring to Fig. 4, the dynamo A, the cross-bondings G, the signals C, the relays K, and the secondary windings e of the transformers E² are the same as in Fig. 3. The primary windings e' of the transformers are shown in Fig. 4 in multiple with the mains of the source L of alternating current, impedance or resistance coils Z being interposed between each winding e' and the main to which it is connected to prevent excessive current in the transformers when the secondaries e are short-circuited by trains. The windings e² of the transformers E² are connected together in pairs and joined to the trolley wire, feeder, or third rail B, the same as the coils Y in Fig. 2. The pairs of windings e² are connected to the wire, feeder, or rail B to the points R and R', which are at some distance from each other, so that there will be a difference of potential between the terminals R and R', due to the resistance of the trolley wire, feeder, or third rail D. The difference of potential causes a current to flow in the coils e² in proportion to the current flowing through the rails and the secondaries e of the transformers E². The number of turns, the direction, and amount of the direct current flowing through the coils e² are such as to neutralize the magnetism of the cores of the transformers caused by the direct current traversing the secondaries e.

One relay K is shown for each section F' and F³ and two for the section F², the number, however, being optional.

On Fig. 5 the parts are the same as on Fig. 2, except that the coils X', which correspond to the coils X of Fig. 2, are not connected between the ends of adjacent rail-sections, as in Fig. 2, but are bridged across the continuous rail M and the ends of the sections of the rail N. The pairs of connected coils X' each have one terminal connected to the rail M, and one of the coils X' has its second terminal connected to the end of one rail-section, and the other of the coils has its second terminal connected to the adjacent end of the adjacent rail-section. The coils Y are connected up

to the system the same as on Fig. 2. All the description of Fig. 2. as to purposes and proportion of parts of the coils X and Y and their connections apply equally well to the 5 coil X' and Y of Fig. 5.

I do not desire to limit myself to the connecting together of two secondaries Y of the transformers X, as three, four, or more secondaries could be connected together.

10 In Fig. 6 the direct-current dynamo A, the feeder wire or third rail B, the rails M and N, the signals C, and relays K have the same characteristics and are connected up the same as on the other figures. The transformers E³, &c., are arranged in pairs. A 15 pair of secondaries e are located at the junctions of the block-sections, one terminal of each pair being connected to the rail M. The second terminal of one of the pairs is connected to the end of one rail-section and the second terminal of the other one of the pair is connected to the adjacent end of the adjacent rail-section. The primaries e⁵ are connected in series with the source L of alternating 25 current. A secondary winding Y' is provided for each member of each pair of transformers, and the secondaries of each pair are connected in series, their terminals being connected to the wire or third rail B at R and R', which are some distance apart, so that 30 there will exist a difference of direct-current potential between them due to the resistance of the wire or third rail B. The windings of the transformer-coils are such that 35 the direct current in the coils e⁵ will neutralize the magnetism of the cores caused by the direct current in the coils e. Of course any number of secondaries Y' could be connected together.

40 In Fig. 6 I have shown the car D on block-section F'. The alternator L through the transformers E³, connected to opposite ends of the section F', normally supplies current to cause the relays K to maintain their 45 switch-arms k bridging the pairs of contacts o of the signal C. So long as the arms k maintain the local circuit of the signal C closed the signal will indicate a clear track, as shown by the signals C at block F². The car 50 D on the block F' short-circuits the relays, which being deprived of the normal flow of alternating current opens the local circuits at the contacts o, whereupon the signal C displays "danger," as shown.

55 It is to be understood that each of the relays K in all the figures is only operable by alternating currents.

It will be seen that in each variety of my invention both the continuous and the sectional rails constitute a return for the direct propulsion-current and that the alternating current furnished to each block-section cannot pass to adjacent sections with sufficient strength to control the signals thereof.

65 I do not limit myself to the precise combi-

nation shown, as the apparatus of each section may be the same or different in all or any number of sections. I do not limit myself in other particulars shown, as many changes may be made which will readily occur to those acquainted with the art to which my invention relates.

Though I have called the element B a "trolley-wire," it may as well be a feeder-wire or third rail.

Though I have shown on Figs. 5 and 6 a leg of each pair of transformers connected to the continuous rail, the two said legs of each pair of transformers would preferably in practice be directly joined together and have a single or common connection with said rail.

What I claim as my invention is—

1. In combination with an electric railway, the trackway of which forms a return for the car-propulsion current and is divided into block-sections by insulation, a power-generator for the car-propulsion current, inductive bonds for conducting the power-current around insulation-points and provided with means for preventing saturation of their cores by the propulsion-current, and a signaling system for the railway comprising a railway-signal for each block-section, a track-circuit for each block-section, an alternating signaling-current for each block-section, and a relay for each block-section which responds to the alternating current of its block-section to control a railway-signal as to one of its operations.

2. In combination with a railway the trackway of which is divided by insulations to form block-sections and which is included in the return-circuit for the car-propulsion current, a generator for the car-propulsion current, a conductor connected with the rails around insulation-points and traversed by the propulsion-current, a core for said conductor, a second conductor for said core also traversed by the propulsion-current to prevent saturation of the core by the propulsion-current flowing through the first conductor, and a signaling system for the block-sections comprising track-circuits, relays and railway-signals controlled by the relays.

3. In combination with a railway the trackway of which is divided by insulations to form block-sections and which is included in the return-circuit for the car-propulsion current, a generator for the car-propulsion current, a conductor connected with the rails around insulation-points, and traversed by the propulsion-current, a core for said conductor, a second conductor for said core also traversed by the propulsion-current to prevent saturation of the core by the propulsion-current flowing through the first conductor, cross-bonds for the trackway, and a signaling system for the block-sections comprising track-circuits, relays and railway-signals controlled by the relays.

4. In combination with a railway the track-rails of which are divided to form block-sections by insulations placed in one of its running rails and both of which are included in the return-circuit for the car-propulsion current, a generator for the car-propulsion current, a conductor connecting two adjacent block-rails, a core for said conductor, a second winding surrounding said core and traversed by the car-propulsion current to prevent saturation of the core, and a signaling system for the block-sections of the railway comprising track-circuits, relays and railway-signals controlled by the relays.
5. In combination with a railway the track-rails of which are divided to form block-sections by insulations placed in one of its running rails and both of which are included in the return-circuit for the car-propulsion current, a generator for the car-propulsion current, a conductor connecting two adjacent block-rails, a core for said conductor, a second winding surrounding said core and traversed by the car-propulsion current to prevent saturation of the core cross-bonds for the track-rails, and a signaling system for the block-sections of the railway comprising track-circuits, relays and railway-signals controlled by the relays.
6. In an electric railway signaling system employing a closed signal-controlling track-circuit, a plurality of block-sections, one rail being divided into insulated sections corresponding to the block-sections, a signal for each block-section, and a plurality of relays controlling one or more of the signals, the relays associated with any section being connected at a plurality of points with the section controlled by the signal.
7. In an electric railway signaling system, the combination of a closed track-circuit, a source of alternating current for said track-circuit, a plurality of block-sections, one of the rails being divided into sections corresponding to the block-sections, a signal for each section operable by said current, an inductive impedance-winding in a connection between adjacent rail-sections, and a supplementary winding connected to a source of direct current, and associated with said impedance-winding whereby the core magnetization caused by the direct propulsion-current traversing the impedance-winding in passing from one rail-section to another is neutralized.
8. In an electric railway signaling system, the combination of a closed track-circuit, a source of alternating current for said track-circuit, a plurality of block-sections, one of the rails being divided into sections corresponding to the block-sections, a signal for each section operable by said current, a plurality of inductive impedance-windings in a connection between adjacent rail-sections, and a supplementary winding connected to a source of direct current and associated with said impedance-windings, the windings being such that the alternating currents induced in the supplementary winding of connected impedance-windings will neutralize each other.
9. In an electric railway signaling system, the combination of closed track-circuits, a source of alternating current for each track-circuit, a plurality of block-sections, one of the rails being divided into sections corresponding to the block-sections, a signal for each section operable by said current, an inductive impedance-winding in connection between adjacent rail-sections, a supplementary winding connected to a feeder wire or rail for the car-motor, and associated with said impedance-winding whereby the core magnetization caused by the direct propulsion-current traversing the impedance-winding in passing from one rail-section to another, is neutralized, and a source of direct current supply for said feeder wire or rail.
10. In an electric railway signaling system, the combination of closed track-circuits, a source of alternating current for each track-circuit, a plurality of block-sections, one of the rails being divided into sections corresponding to the block-sections, a signal for each section operable by said current, a path of high impedance to the alternating current from one rail-section to an adjacent rail-section, and a source of direct current associated with said impedance to neutralize the action therein of the direct propulsion-current derived from the track.
11. In an electric railway signaling system, the combination of closed track-circuits, a source of alternating current for each track-circuit, a plurality of block-sections, one of the rails being divided into sections corresponding to the block-sections, a signal for each section operable by said current, a path of high impedance to the alternating current from one rail-section to an adjacent rail-section, and a source of direct current associated with said impedance to neutralize the action therein of the direct propulsion-current derived from the track, said source having a definite ratio to the said current derived from the track.
12. In an electric railway signaling system, the combination of closed track-circuits, a source of alternating current for each track-circuit, a plurality of block-sections, one of the rails being divided into sections corresponding to the block-sections, a signal for each section operable by said current, a path of high impedance to the alternating current, from one rail-section to an adjacent rail-section, and a source of direct current associated with said impedance to neutralize the action therein of the direct propulsion-current derived from the track, said source being variable so as to maintain a definite ratio to the said current derived from the track.

13. In an electric railway signaling system, the combination of closed track-circuits, a source of alternating current for each track-circuit, a plurality of block-sections, one of the rails being divided into sections corresponding to the block-sections, a signal for each section operable by said current, a path of high impedance to the alternating current from one rail-section to an adjacent rail-section, and a supplemental source of direct current associated with said impedance to neutralize the action therein of the direct propulsion-current derived from the track, said supplemental source of current being governed by the return direct propulsion-current on the track.

14. In an electric railway signaling system, the combination of closed track-circuits, a source of alternating current for each track-circuit, a plurality of block-sections, one of the rails being divided into sections corresponding to the block-sections, a signal for each section operable by said current, and means for insulating the alternating current

in one rail-section from the adjacent rail-section, an inductive cross-bonding connecting the rails and having a low resistance to direct current, and a high impedance to the alternating signal-current, and a winding associated with the cross-bonding to neutralize the magnetization of the core thereof caused by the return propulsion-current on the track.

15. In an electric railway signaling system employing closed signal-controlling track-circuits, a plurality of block-sections, one rail being divided into insulated sections corresponding to the block-sections, a signal for each block-section, a relay controlling the signal and operative by current from a plurality of points in the track-circuit of the block-section for which the signal is provided

Signed at Pittsburg this 24th day of December, 1903.
